CLAIM

The ornamental design for a packaging box as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a packaging box, showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is an unfolded view of the packaging box.

The text “Gloryland” as well as the four Chinese characters directly below this text and the leaf graphic directly above this text appearing in FIGS. 1-3 and 8 are a registered trademark and form part of the claimed design. The owner of this trademark is Dalian HongRen Whole Grain Food-stuffs Co.,Ltd.

1 Claim, 8 Drawing Sheets
